OIL BURNER

Joseph Fioroni, Westfield, Mass.

Application March 31, 1933, Serial No. 663,793

3 Claims. (Cl. 158—86)

This invention relates to improvements in oil burners.

An object of the invention is to provide a burner that will automatically shut off the flow of

5 the oil to the burner, when, for any reason, the burner becomes extinguished, or, when in the act of lighting the burner, the wick does not take fire.

A further object is to provide means for adjusting the burners, so that they can be moved laterally, with reference to each other. This is desirable, since the burners are designed to be located in an ordinary kitchen range, when they are substituted for the ordinary coal grates. This 15 adjustment is effective through a ball and socket joint construction, through which joint the oil passes from the supply to each of the burners.

Heretofore, it has been a common practice to adjust the burners with a ball and socket joint, 20 but with no means of conveying the oil directly through the ball part of the joint itself. This feature has been combined with the lateral adjustment of the burners.

A further object is to provide means for thoroughly straining the liquid oil fuel, before it is delivered to the base portion of the burners. This is accomplished by locating, in a bowl member, which is located between the burners and the main supply of oil to the burners, by having in 30 this bowl, two fine wire mesh strainers; one being placed around the entrance end of the pipe that conveys the oil to the burners, and the other strainer is located above the entrance end and at the lower end of the oil container, wherein the 35 supply of oil is located. These, and other objects will appear in the body of the specification and be pointed out in the claims.

Referring to the drawings:—

Fig. 1 is an elevational view, showing the complete assembly of the two burners.

Fig. 2 is a vertical sectional view on the line 2—2 of Fig. 1.

Fig. 3 is a detail sectional view, showing the bowl construction.

45 Fig. 4 is a top plan view, partially in section, showing, in detail, the adjustable feature of the burners.

Fig. 5 is a detail sectional view on the line 5—5 of Fig. 4.

50 Fig. 6 is a horizontal plan view of the base part of the burner, in section, on the line 6—6 of Fig. 7.

Fig. 7 is a sectional view, on the line 7—7 of Fig. 6, showing one of the burners, in section, 55 and illustrating, in detail, one of the ball and

socket joint constructions, and the adjustable feature for the burner.

Fig. 8 is a detail vertical sectional view on the line 8—8 of Fig. 7.

Fig. 9 is a vertical sectional detail view, on 60 the line 9—9 of Fig. 7.

Referring to the drawings in detail:—

1 indicates the post, or standard, which supports the oil supply receptacle, indicated at 2. 3 is a bowl member at the lower end of the oil receptacle, which is provided with the shoulder 4, on which is supported the cup-shaped member 5, that is formed with an opening 6. Located within the cup-shaped member 5, is a U-shaped member 7, on which is placed the fabric, or 70 cushion 8, to protect the lower end of the receptacle 2. The member 7 and the cushion 8 are formed with the opening, or oil passageway 9, in which is located the stem 10 of the valve 11. The lower end of the stem is formed with a head portion 12, on which rests the lower end of the conical-shaped coiled spring 13. The upper end of the coiled spring rests against the bottom of the member 7, in the opening 6. The stem 10 rests on the cup-shaped member 14, which is supported on the two brackets 15 of the bowl 3; also, resting on these brackets, is the fine wire strainer 16, which, as shown, is spaced from the bowl, indicated at 17. Located in the bottom portion of the bowl, is the threaded opening 18 for the pipe 80 connection 19, which is attached to the angle coupling 20. 21 is the supply pipe that is connected with the angle coupling 20. The pipe 19 extends upward into the bowl, as shown at 23. The pipe 23 is formed with the fuel openings 24. 85 25 indicates a fine wire screen placed over the pipe 23, with the openings therein. The weight of the container, indicated at 2, on the cup-shaped member 7, will cause the valve passageway 9 to open permitting the oil to flow through this 90 opening into the fine wire strainer 16, through the sides of the same, and then downward into the lower part of the bowl 3, where it passes through the fine wire strainer 25, into the pipe 21. From here, the oil passes to the control valves 26 and 27, which control the flow of the same to each of the burners 28 and 29, by means of the pipes 30 and 31. The oil then flows upward 100 through the passage 32 in the ball and socket joint member 33 into the central receiving basin 34, at the center of the base 28 of the burner.

This ball and socket joint construction comprises two plates 35 and 36, as shown in section, in the sectional view in Fig. 5, which are connected together by means of the bolt 37 that 110

passes through the slot, or opening 38 of the member 40, that is secured to the post 42. These two plate members, 35 and 36, have a spherical, or curved, seat, which receives the bulb member 33, and are clamped together, at their outer ends, by the bolt 41. 42 indicates a standard that supports the two burners 28 and 29 and to which the plates 35 and 36 are connected by the ball and socket joint. 42' is a set screw for the member 40. By loosening the bolt 37, the two burners may be laterally adjusted, relative to each other, by means of the slot and bolt construction, 37 and 38. Also, the two burners may be carefully positioned in a horizontal plane, by means of the ball and socket joint construction, shown in detail, in Fig. 7. As the oil flows through the pipe 21, past the control valves 26 and 27, it enters the base of the burner through the pipes 30 and 31, through the passageways 32, into the central bowl 34. From this point, it flows in the usual manner, through the radial passageways 43 to the two annular grooves 44 and 45, in which are placed the burner wicks 46 and 47. Resting on the upper edges of the groove members, are the usual perforated cylinders 48, 49, 50, and 51. The usual, centrally located passage is indicated at 52. 53 indicates the two return, or overflow pipes, connected with each of the bases of the burners, 28 and 29, that are connected to the pipe 54 that enters the bottom portion of the casing 55, (see Fig. 2), in which is located the float 56, that is connected to the rod 57 having a button 58, at its upper end. This rod is pivotally connected to the two-armed lever 59 that carries, at its opposite end, the rod 60 and the valve 61. As shown in Fig. 2, the valve 61 is open, permitting oil to flow through the pipe 21 to each of the burners. Should the flame on either one of the burners go out, causing the channels 44 or 45 to fill with oil, and overflow into the passages 62, the oil would then flow down the pipes 53 and into the bottom of the casing 55 by the pipe 54. This would cause the float 56 to rise and force the valve 61 to its seat, thus shutting off the main flow of the oil, through the pipe 21, preventing the oil from escaping onto the floor. When the operator wishes to restart the burner, he pushes downward on the button 58, forcing the float 56 downward and bringing the valve 61 into its open position, permitting the oil to again flow through the pipe 21. At the same time, the oil is prevented from flowing backward in the pipe 54, by reason of the check valve 64, but will flow past the check valve 66, into the pipe 67, and by means of the pipe 68, into the supply pipe 21, or back into the bowl 3.

An important feature of my invention is that the bottom of the wick-receiving channels, 44 and 45, extend downward, as shown at 69, which channels permit the lower edges to be submerged in the oil, as shown in Fig. 7.

From this description, it will be seen that I have provided an oil burner that may be readily adjusted laterally towards and from each other; also, a burner that can be adjusted horizontally and one that takes care of any overflow of oil; and, means for carefully straining the oil, before it is delivered to the burners.

The operation of the apparatus may be described, as follows:—

Consider the oil as flowing downward from the

oil supply tank 2, through the opening 9, through the fine wire mesh strainer 17, into the lower portion of the bowl 3, then through the fine wire screen 25 to the openings 24, in the pipe 23, then through the pipe 21, in the direction of the arrow shown in Fig. 1. It now flows past the open valve 61, shown in Fig. 2, through the second, or right hand length of the pipe 21, to the two burner control valves 26 and 27 (see Fig. 4), through the pipes 30 and 31, through the passageways 32 in the ball and socket joint 33 to the central oil-receiving basins 34 of the burners 28 and 29. From the central bowl, or basin, it flows through the radial passageways 43 to the two annular grooves 44 and 45, in which the wicks 46 and 47 are placed. These wicks, as shown in Fig. 7, are located between the usual perforated cylinders.

In the event the flame of the burners should go out, the oil in the grooves 44 and 45 will fill and flow through the grooves 62 to the overflow pipes 53 which are connected to the return pipe 54, past the valve 64 into the bottom of the casing 55, shown in Fig. 5. This overflow oil will raise the float 56, which will operate to close the valve 61 in the supply pipe 21, leading to the burners. When the valve 61 remains closed, the oil from the tank 2 cannot flow through the pipe 67, because of the check valves 64 and 66 therein. With the parts in this position, in order to restart the burner, it is only necessary for the operator to press downward on the button 58, which will move the float 56 downward and open the valve 61 in the supply pipe 21, whereby any oil in the return pipe 67 will be forced, by the downward movement of the float, into the supply pipe 21. The wicks of the burners may now be relighted.

What I claim is new is:—

1. In an oil burner construction, a burner base member, a supporting pedestal, an arm on the pedestal formed with a slot, a pair of plates having bolt-receiving openings, a bolt in the openings and passing through the slot in the arm, the plates having curved recessed ends, a spherical member on the burner base formed with an oil passage which is clamped in place by the curved recessed plates, and means for drawing the plates together onto the spherical member.

2. An oil burner comprising in combination, a supporting pedestal, a plurality of burner members, means on the pedestal for adjustably spacing said burners relative to each other, and to the pedestal, means on the adjustable spacing means for adjusting the burner in a horizontal plane comprising a ball and socket construction, and means for conducting oil to the burner through the ball and socket construction.

3. In an oil burner having a base member, a pedestal for supporting the base member, a slotted arm on the pedestal, and plate members slidably secured on said arm, said base member being formed with a depending part that is substantially spherical and having an oil passage therethrough, said plate members having spherical-shaped surfaces engaging the spherical-shaped part of said base member, whereby the base member may be levelled and laterally adjusted relative to the pedestal, as described.

JOSEPH FIORONI.
